UNITED STATES PATENT OFFICE.

SAMUEL KATZ, OF NEW YORK, N. Y.

SAFETY GAS-BURNER.

No. 820,647.

Specification of Letters Patent.

Patented May 15, 1906.

Application filed January 15, 1906. Serial No. 296,129.

To all whom it may concern:

Be it known that I, SAMUEL KATZ, a citizen of the United States, residing at New York, in the county of New York and State of New York, have invented certain new and useful Improvements in Safety Gas-Burners, of which the following is a specification, such as will enable those skilled in the art to which it appertains to make and use the same.

10 This invention relates to gas illuminating burners, and the object thereof is to provide a burner of this class which is so constructed that if the gas should at any time be extinguished without cutting off the flow thereof 15 to the burner the said flow of gas to the burner will be automatically cut off; and with this and other objects in view the invention consists in a burner of the class specified constructed as hereinafter described and claimed.

20 The invention is fully disclosed in the following specification, of which the accompanying drawings form a part, in which the separate parts of my improvement are designated by suitable reference characters in each 25 of the views, and in which—

Figure 1 is a central vertical section of a gas-burner made according to my invention; Fig. 2, a transverse section on the line 2 2 of Fig. 1, and Fig. 3 a transverse section on the 30 line 3 3 of Fig. 1.

In the drawings forming part of this specification I have shown an ordinary gas-supply pipe a , provided with a valve a^2 and a burner-attachment member a^3 , and in the practice of 35 my invention I provide a burner comprising a tube b , provided at its lower end with a reduced coupling member b^2 and the upper end of which is closed and provided with ports or passages b^3 , which are arranged concentrically 40 around the central axis of the tube b in the form of construction shown.

Mounted on the tube b is a vertically-movable sleeve member c , the lower end of which is open and the upper end of which is closed 45 and provided centrally with a nipple-receiving tubular extension c^2 , adapted to receive an ordinary burner-nipple d , and in practice I preferably form in the top surface of the 50 end of the tube b and in the bottom surface of the top of the sleeve member c and around the opening formed by the tubular extension c^2 an annular groove c^3 , in which is placed a packing-ring of any suitable material, preferably fibrous material saturated with paraffin 55 or other preservative liquid. Secured to the tube b below the sleeve member c is a collar

or band f , to one side of which is secured one arm of a yoke-shaped thermostat g , the other arm of which extends downwardly on the opposite side of the tube b to a predetermined point and is provided with an outwardly-directed finger g^2 . That side of the collar or band f opposite the point where one of the arms of the yoke-shaped thermostat g is secured thereto is provided with an upwardly-directed member f^2 , having a vertically-arranged slot or opening f^3 , above which said member f^2 is provided with an outwardly-directed projection f^4 , on which the finger member g^2 of the thermostat g rests, and said finger member g^2 passes through a keeper f^5 , secured to the projection f^4 . The lower end of the sleeve member c is provided with an outwardly-directed arm h , having an upwardly-directed member h^2 , provided with an inwardly-directed hook member h^3 , in connection with which the finger g^2 of the thermostat g operates, and the arm h is provided with a downwardly-directed rod i , which forms a handle for manipulating the sleeve member c in the process of lighting the burner or igniting the gas that escapes from the nipple d . The tube b is also provided in the form of constructing shown with a perforated partition j , which operates to regulate, to an extent, the flow of the gas through the burner; but said tube may be provided with any desired kind or class of a regulator.

The operation of this device will be readily understood from the foregoing description when taken in connection with the accompanying drawings and the following statement thereof. Whenever it is desired to light the burner, the valve a^2 is opened, the sleeve c is raised by means of the rod i , and the gas is allowed to flow through the burner and through the burner-tip d and is ignited in the usual manner. The flame of the gas striking the top portion of the thermostat g immediately expands the same, and this expansion throws out the finger g^2 beneath the hook member h^3 , which is raised, as before described, in the operation of igniting the gas, and when this is done the rod i may be released, and as long as the burner is ignited or in operation the finger g^2 , operating in connection with the hook member h^3 , will hold the sleeve c in its raised position. If at any time the gas should be extinguished without cutting off the flow thereof, the thermostat g will immediately contract and the finger g^2 will be withdrawn from beneath the hook

member h^3 and the sleeve c will drop into the position shown in full lines in Fig. 1, and the flow of gas to the burner-tip will be cut off.

In practice the thermostat g is preferably 5 made of different metals possessing different degrees of expansibility under heat in order that the operation thereof will be more quickly affected by the heat of the burner; but my invention is not limited to the material employed in the construction of the thermostat.

It will also be understood that when the sleeve c is in its lowest position, as shown in full lines in Fig. 1, the gas cannot escape from 15 the tube b , as the top of the sleeve c rests directly on the top of said tube, and these parts may be so made as to prevent the escape of gas, and the packing-ring e also serves to aid in accomplishing this result.

20 Having fully described my invention, what I claim as new, and desire to secure by Letters Patent, is—

1. A gas-burner of the class described, comprising a tube adapted at its lower end to be 25 connected with a gas-supply pipe, said tube being closed at its upper end and provided with concentrically-arranged ports or passages, a sleeve mounted on said tube and closed at its upper end and provided centrally with a burner-tip, a collar secured to said tube below said sleeve, a yoke-shaped thermostat one arm of which is secured to said collar and the other arm of which is provided with an outwardly-directed finger, and 30 an arm connected with the lower end of said sleeve and provided with an inwardly-directed hook member in connection with which said finger operates, substantially as shown and described.

40 2. A gas-burner of the class described, comprising a tube adapted at its lower end to be

connected with a gas-supply pipe, said tube being closed at its upper end and provided with concentrically-arranged ports or passages, a sleeve mounted on said tube and 45 closed at its upper end and provided centrally with a burner-tip, a collar secured to said tube below said sleeve, a yoke-shaped thermostat one arm of which is secured to said collar and the other arm of which is provided with an outwardly-directed finger, an 50 arm connected with the lower end of said sleeve and provided with an inwardly-directed hook member in connection with which said finger operates, and means for raising 55 said sleeve, substantially as shown and described.

3. A gas-burner of the class described comprising a tube the lower end of which is adapted to be connected with a gas-supply pipe, 60 said tube being closed at its upper end and provided with concentrically-arranged ports or passages, a vertically - movable sleeve mounted on and movable on said tube and the upper end of which is closed and provided 65 centrally with a burner-tip, said sleeve being adapted in its lowest position to cut off the flow of gas from the burner-tip and in its raised position to permit of said flow, and a thermostat connected with said tube and 70 adapted to operate in connection with a part connected with said sleeve to hold said sleeve in its raised position, substantially as shown and described.

In testimony that I claim the foregoing as 75 my invention I have signed my name, in presence of the subscribing witnesses, this 12th day of January, 1906.

SAMUEL KATZ.
